H. J. DERBY,
DEVICE FOR STOPPING TRAINS OR CARS,
APPLICATION FILED JUNE 5, 1916.

1,347,996.

Patented July 27, 1920.

UNITED STATES PATENT OFFICE.

HOLLIS J. DERBY, OF AMHERST, OHIO.

DEVICE FOR STOPPING TRAINS OR CARS.

1,347,996.

Specification of Letters Patent. Patented July 27, 1920.

Application filed June 5, 1916. Serial No. 101,815.

To all whom it may concern:

Be it known that I, HOLLIS J. DERBY, a citizen of the United States, residing at Amherst, in the county of Lorain, State of Ohio, have invented certain new and useful Improvements in Devices for Stopping Trains or Cars; and I do hereby declare the following to be a full, clear, and exact description of the invention, such as will enable others skilled in the art to which it appertains to make and use the same.

This invention relates to a device for stopping trains or cars.

An object of the invention resides in the provision of an improved mechanism which will be automatic in its operation.

A further object of the invention resides in so constructing the device that it may be readily installed and so that its operation will be positive and will apply the air brakes or close the throttle.

With these and other objects in view, such as will appear as my description progresses, my invention comprises the combination and arrangement of parts as set forth in and falling within the scope of the appended claims.

In the drawing:

Figure 1 is a side elevation of the preferred embodiment of my invention showing the same attached to the throttle controlling arm;

Fig. 2 is a longitudinal sectional view of the same;

Fig. 3 is a plan view, and

Fig. 4 is an elevation of a modification of my device;

Fig. 5 is a diagram showing how this mechanism is actuated as the locomotive passes a signal.

Referring to the embodiment of the invention illustrated in Figs. 1 to 3 inclusive, I have provided a cylinder 1 which is closed at its inner end by a cap 2 which has a centrally located opening 3 therein and at its outer end by a threaded plug or cap 4 which has a threaded opening therein. This cylinder 1 is supported on a bracket 5 by means of clamps 6, which bracket is provided with an arm 7 extending at right angles to the body portion thereof and is adapted to be secured to a suitable portion of a locomotive or car. A piston 9 is mounted and operable in the cylinder 1 and is provided with a rod 10 which extends through the opening 3 in the cap 2 and slidably through an opening 11 in the arm 7. This rod is provided with a shoulder 12 which is adapted to abut against the cap 2 to limit the movement of the piston in one direction, which movement is resisted by a coil spring 13 which encircles the rod and bears at one end against the arm 7 and at the other end against a sleeve 14 which is secured to the rod externally of the cylinder. This cylinder is also provided with an exhaust port 15 opening laterally at about its midlength, and normally the piston 9 stands between this port and the cap 4 while the shoulder 12 stands between the port and the cap 2. The space within the cylinder between the piston and cap 4 constitutes an expansion chamber, and within it may be disposed an explosive material, introduced by removing the cap as will be clear. Through the opening of this cap is screwed a spark plug 16, shown diagrammatically in Fig. 1 as included in an ignition circuit 17 which leads through an interrupter and a normally open circuit closer or switch 17'. From the shaft of the latter rises a finger F standing in position to strike a semaphore signal S carried by a post P alongside the track, when said signal is set at danger as seen in Fig. 5. This closes the switch 17' and produces a spark in the gap of the plug 16 and by this spark the explosive material will be ignited and the piston 9, rod 10, and sleeve 14 will be moved longitudinally. This sleeve 14 is adapted to be connected to one of the motive power levers 18 so that when it is moved the throttle will be closed or the air brakes applied. As the piston moves past the exhaust port 15 the gases resulting from the explosion within the expansion chamber will pass from the cylinder by way of the port. The inward movement of the rod is limited by the contact of the shoulder 12 with the inner cap 2, at which time the piston has passed well beyond the port, the spring 13 is compressed considerably, and the lever 18 moved to its opposite extreme position. If this lever be a crank fast on the stem of a valve, the plug thereof will have been rotated a full quarter revolution. While the fluid within the chamber expands suddenly when ignited and exploded as explained, the gases escape rapidly through the port 15 and the piston immediately reacts under the expansive force of the spring 13, passing quickly back to the port and then moving more slowly into the

explosion chamber because of the rather close fit of the piston within the cylinder. It follows that after the action of the device to throw the lever, it will immediately react to swing the lever back a certain distance, and then continue to react more deliberately.

In Fig. 4 of the drawing, I have illustrated two elements A and B, the element A being identical with the embodiment shown in Figs. 1 to 3 inclusive and inasmuch as this is true I will not enter into a detailed description of this element A but will designate the similar parts by similar reference characters primed. The sleeve 14' is connected to a valve actuating arm 19, which arm is connected to a valve 20 in an air or steam pipe 21, which pipe leads from a suitable storage tank or boiler 22. The element B is likewise similar to the embodiment shown in Figs. 1 to 3 inclusive with the exception that the spark plug at the outer end of the cylinder is omitted and the pipe 21 is connected to the cylinder by way of the opening in the cap 4. In this element parts similar to those of the element A are designated by similar characters primed. The sleeve 14' on the element B carries an arm 18' which is connected to the motive power lever, as shown.

In the operation of this embodiment the explosion occurs in the element A, which explosion operates the arm 19 so that the valve 20 is opened and the air or steam passes through the pipe 21 to the expansion chamber of the cylinder of the element B. The entrance of the air or steam in this chamber causes the rod 13' to move and actuate the lever 18' so that the locomotive or car will be stopped. In this embodiment of the invention, however, pressure continues to flow from the tank 22 into the element B as long as the valve 20 remains open, and therefore the piston within this element will not react into the expansion chamber, because fluid is constantly flowing out the port 15'. The valve 20 will not close until the piston within the element A resumes substantially its original and normal position. Hence it will be seen that, in both embodiments of the invention the restoration of parts to normal depends on the force of the spring 13, the looseness of the piston within the cylinder, and the extent of movement imparted to the lever

or other member 18, and therefore the distance it must move back in order to resume its original position.

While I have illustrated and described a particular embodiment of my invention, it has merely been for the sake of convenience and I do not wish to be limited to that particular embodiment as it is obvious that numerous changes may be made in the details of construction without departing from the spirit of the invention or exceeding the scope of the appended claims.

What I claim is:—

1. In a device of the class described, the combination with a cylinder having perforated caps at its ends and an exhaust port at about its midlength, a spark plug in the perforation of the outer cap and included in an ignition circuit, a piston within the cylinder between this cap and said port, the space between such cap and piston constituting an expansion chamber adapted to contain an explosive, and means for closing said circuit; of a rod leading from the piston through the perforation in the inner cap, a shoulder fixed on the rod in position to strike this cap when the piston has passed said port, a spring bearing the rod and piston normally inward, and a lever connected with and actuated by movements of said rod.

2. In a device of the class described, the combination with a cylinder having perforated caps at its ends and an exhaust port at about its midlength, a spark plug in the perforation of the outer cap and included in an ignition circuit, a piston within the cylinder between this cap and said port, the space between such cap and piston constituting an expansion chamber adapted to contain an explosive, and means for closing said circuit; of a rod leading from the piston through the perforation in the inner cap, a fixed arm having a guide opening for said rod, a sleeve fast on the rod, an expansive spring coiled on the rod between the sleeve and guide, and connections between the sleeve and a motive power lever.

In testimony whereof, I affix my signature, in the presence of two witnesses.

HOLLIS J. DERBY.
